US00D781990S

(12) **United States Design Patent** (10) **Patent No.:** **US D781,990 S**
(45) **Date of Patent:** **** Mar. 21, 2017**

(54) **FIREARM SCOPE**

(71) Applicants: **Carson Cheng**, City of Industry, CA (US); **Jason Michael Cheng**, City of Industry, CA (US); **Richard Thomas**, City of Industry, CA (US)

(72) Inventors: **Carson Cheng**, City of Industry, CA (US); **Jason Michael Cheng**, City of Industry, CA (US); **Richard Thomas**, City of Industry, CA (US)

(73) Assignee: **N cSTAR, Inc.**, City of Industry, CA (US)

(**) Term: **15 Years**

(21) Appl. No.: **29/553,714**

(22) Filed: **Feb. 3, 2016**

(51) LOC (10) Cl. **22-01**

(52) U.S. Cl.

USPC **D22/109**

CLAIM

The ornamental design for a firearm scope, as shown and described.

DESCRIPTION

FIG. 1 is a perspective view of a firearm scope showing our new design.

FIG. 2 is a rear view of the firearm scope.

FIG. 3 is a front view of the firearm scope.

FIG. 4 is a right view of the firearm scope.

FIG. 5 is a left view of the firearm scope.

FIG. 6 is a top view of the firearm scope.

FIG. 7 is a bottom view of the firearm scope; and,

FIG. 8 is a perspective view of the firearm scope, illustrating a reflex sight detachably coupled on the firearm scope.

The broken lines in the drawing figures show environmental

subject matter and form no part of the claimed design.

1 Claim, 8 Drawing Sheets
